SANITARY SHOWER STALL

Nolan B. Wicker and Johnny B. Whelchel,
Joanna, S. C.

Application December 6, 1948, Serial No. 63,766

7 Claims. (Cl. 4—146)

1

This invention relates to a shower stall and more especially to means for spraying onto the feet of the user of the shower stall a mixture of water and an antiseptic fluid, whereby the feet of the user will be disinfected at the same time he takes a shower.

It is an object of this invention to provide, in combination, a shower stall having a conventional shower head and to provide on the floor of the shower stall a plurality of perforated pipes on which the bather may stand, together with means for forcing a mixture of water and an antiseptic fluid through the perforations in the pipes onto the feet of the user.

It is another object of this invention to provide means for regulating the proportionate amounts of water and antiseptic fluid which are forced through the pipes on the floor of the shower, and to also provide means whereby the flow of fluid through the perforated pipes may be entirely stopped, if so desired.

Some of the objects of the invention having been stated, other objects will appear as the description proceeds, when taken in connection with the accompanying drawings, in which

Figure 1 is an elevation of a conventional shower stall, with parts broken away and showing other parts schematically, and showing the invention associated therewith;

Figure 2 is a sectional plan view taken along the line 2—2 in Figure 1 and showing the floor of the shower stall and the perforated pipes disposed thereon;

Figure 3 is an enlarged vertical sectional view of the diaphragm valve shown in the upper portion of Figure 1;

Figure 4 is an enlarged vertical sectional view taken along the line 4—4 in Figure 1;

Figure 5 is a vertical sectional view taken along the line 5—5 in Figure 4;

Figure 6 is a vertical sectional view taken along the line 6—6 in Figure 2;

Figure 7 is a vertical sectional view on an enlarged scale, taken along the line 7—7 in Figure 6.

Referring more specifically to the drawings, the numeral 10 indicates the wall of a suitable shower stall which is adapted to be placed in a building, the numerals 11 and 12 indicating hot and cold water pipes, respectively, the pipes 11 and 12 being connected to any suitable source of hot and cold water, respectively. The hot water pipe 11 is provided with a conventional manually operable control valve, having a suitable handle 14 secured thereto as by a screw 15, while the

2

cold water pipe 12 has a similar manually controlled valve provided with a handle 17 secured thereto as by a screw 18. The handles 14 and 17 are provided with annular spacer rings 13 and 16, respectively, which fit against the wall of the shower stall. Extending from the valves in the pipes 11 and 12, respectively, are branch pipes 19 and 20, which are joined together by a conventional pipe T 21. Extending upwardly from this pipe T 21 is a pipe 22, and this pipe 22 has intermediate its ends another pipe T 23, and the upper end of the pipe 22 extends through the shower wall 10 and has a conventional shower head 24 secured thereon in any suitable manner, the lower surface of this shower head being provided with a plurality of perforations 25 through which water is adapted to be forced.

Extending from the pipe T 23 is a branch pipe 26, to the left-hand end of which in Figure 1 is secured a pipe elbow 27 and this pipe elbow 27 has an uprising branch pipe 28, to the upper end of which is connected an elbow 29, from which extends another branch pipe 30, to the right-hand end of which in Figure 1 is secured an elbow 31. A pipe 32 connects the lower end of the elbow 31 to the upper end of a valve housing broadly indicated at 33.

This valve housing 33, as may be clearly seen in Figure 3, comprises an upper outer casing 35 and a lower casing 36, and these two casings have, at their proximate edges, out-turned flanges 37 and 38, respectively, between which is adapted to be disposed a resilient and flexible diaphragm member 40, and the two flanges 37 and 38 are secured to each other by means of a plurality of threaded screws 41 which penetrate the two flanges 37 and 38 and the resilient and flexible diaphragm member 40, and these screws 41 are secured in threaded bores in the flange 38. It will be noted that the resilient member 40 serves as a gasket to prevent the escape of water from the valve housing 33. The upper end of the casing 35 is threaded on its interior surface and a hollow plug 45 is adapted to be threaded into the upper end of the casing 35, and this plug 45 is internally threaded for the reception of the pipe 32.

Disposed at the center of the diaphragm member 40 is a round hole through which is adapted to project a rod 50, whose upper end is threaded, and this rod 50 has a nut 51 disposed thereon below the member 40, which is adapted to normally engage the lower surface of the member 40, and there is disposed above the diaphragm member 40 another nut 52, the lower surface of which

is convex and is adapted to engage the diaphragm member 40, the nuts 51 and 52 being threaded on the rod 50. The convex surface of nut 52 prevents rupture of the diaphragm 40.

Secured to the lower end of the rod 50 is a valve closure member 55 which is adapted to normally engage a valve seat 56 disposed in the lower casing 36. The rod 50 extends slightly below the valve closure member 55 and has disposed therearound a compression spring 60, the lower end of which is disposed around a projection 61, extending upwardly from a plug 62 threadably secured in the lower portion of a hollow plug 63, which is identical to the plug 45, and which is threadably secured in the lower end of the casing 36.

Secured in the right-hand portion of the casing 36 is a pipe 70 which extends to the right and upwardly in Figures 1 and 3 and its upper end is secured in one side of a valve housing 75 in which is mounted a manually operable valve 76 having a handle 77 thereon. The upper open end of the valve housing 75 is mounted in the bottom of a tank 80. The valve 76 may be moved to closed position to prevent passage of fluid into the pipe 70 from the storage tank 80, this tank being adapted to contain any suitable antiseptic solution or germicide. It is obvious that in normal operation of this apparatus the valve 76 would remain in open position, but this valve may be closed if it is desired to eliminate the use of the apparatus.

Extending from and secured in the left-hand portion of the upper casing 35, is a pipe 85, and to the left-hand end of which is threadably secured an elbow 86, and this elbow has threadably secured therein and extending downwardly therefrom another pipe 87, the lower end of which is adapted to be threadably secured in a valve housing 88. Extending from and secured in the left-hand portion of the lower casing 36, in Figures 1 and 3, is a pipe 90, to the left-hand end of which is threadably secured an elbow 91 and this elbow 91 has a downwardly extending pipe 92 threadably secured therein. Threadably secured to the lower end of pipe 92 is another elbow 93, and this elbow 93 has a short pipe 94 threadably mounted therein at its right-hand end, the left-hand end of this pipe 94 being threadably secured in the valve housing 88.

Disposed above the point of connection of the short pipe 94 to the valve housing 88 is a valve 100, best shown in Figure 4, and this valve 100 has secured on its outer end a handle 101, as by a screw 102, and the handle 101 is adapted to be rotated in a clockwise direction in Figure 1 to close the valve 100 when so desired.

Extending from and threadably mounted in the lower portion of the valve housing 88 is a pipe 105, whose lower end is adapted to be connected to an elbow 106 and this elbow 106 is connected at its right-hand end in Figure 2 to a pipe or tubular member 107, the right-hand end of which in Figure 2 is closed.

This tubular member 107 has a plurality of flat-topped pipes 110 secured therein, by any suitable means such as welding, and each of these pipes 110 has a plurality of perforations 111 in the flat top thereof, and the user of the shower normally rests his feet on the top surface of these pipes 110 while using the shower. It will be noted that the top surfaces of all of the pipes 110 are in the same horizontal plane.

Each of the pipes 110 is closed at its end opposite from the tubular member 107, and there is

another tubular member 115 secured to the closed end of each of the pipes 110 for the purpose of supporting the same, as is shown in Figures 2 and 6. There is disposed in one corner of the area defined by the pipes 110 a plate 120 on which the user of the shower may stand while he regulates the flow of water to the shower.

Each of the tubular members 107 and 115 is adapted to rest on the floor 121 of the shower stall, and the shower stall is provided with a conventional drain 122, for draining water from the shower stall.

In operation, the user of the shower stands on the plate 120 and turns the handles 14 and 17 to open their respective valves to thus admit water from the pipes 11 and 12, through the pipes 19, 20 and 22 to the shower head 24 and thus the water is forced through the perforations 25. Now, as the water flows through the pipe 22, it will flow into the pipe 28 and through the pipes 28 and 30 to the upper end of the casing 35. As the water enters the upper casing 35, since it is under pressure, it will force the resilient diaphragm member 40 downwardly, against the compression of spring 60, which will open the valve 55, through the rod 50, and this will permit the antiseptic fluid in the tank 80 to flow through the pipe 70 into the right-hand side of the lower casing 36.

The water after entering the upper casing 35 and forcing the resilient member 40 downwardly, will flow through the pipe 85, the elbow 86 and the pipe 87 into the valve housing 88. At the same time, the antiseptic fluid will flow through the pipes 90, 92 and 94 into the lower portion of the valve housing 88, and with the valve 100 in open position, the antiseptic fluid and the water will be mixed together in the valve housing 88 and will then flow as a mixture through the pipe 105 and the elbow 106 into the tubular pipe 107 and thus into the perforated flat-topped pipes 110, which will allow the mixture of water and antiseptic fluid to escape through the perforations 111. The antiseptic fluid may have a suitable perfume mixed therewith, if desired.

After the user of the shower has adjusted the water to the desired temperature, he will step from the plate 120 onto the pipes 110, and it is thus seen that only water will flow from the shower head 24, through the perforations 25, onto the user's body, and that the mixture of water and antiseptic fluid will flow from the perforations 111 onto the feet of the user, thereby serving to disinfect the feet of the user.

It is manifest that the proportionate amounts of water and antiseptic fluid being forced through the pipes 110 may be regulated by means of the manually controlled valve 100, or by valve 76, or both of these valves.

By means of the valve 76, the rate of flow of the antiseptic fluid from the tank 80 may be regulated, or the flow of antiseptic fluid may be entirely shut off by closing completely the valve 76, and with the valve 100 in closed position, no water or antiseptic fluid would be caused to flow through the pipes 110.

It is thus seen that means have been provided whereby antiseptic fluid may be sprayed onto the feet of the user of a conventional shower bath and whereby the concentration of the antiseptic with relation to the water may be regulated, or the flow of water and antiseptic fluid to the feet of the user may be entirely stopped.

In the drawings and specification there has been set forth a preferred embodiment of the in-

vention, and although specific terms are employed, they are used in a generic and descriptive sense, only, and not for purposes of limitation, the scope of the invention being defined in the claims.

We claim:

1. In a shower bath comprising a floor, side walls, a drain, a source of supply of hot water, a source of supply of cold water, a shower head, and means for regulating the flow of hot and cold water to the shower head, a storage tank for antiseptic fluid and the like, a plurality of perforated pipes disposed on the floor of the shower, a pipe line connecting the tank for the antiseptic fluid to the plurality of perforated pipes disposed on the floor of the shower, a pipe line connecting the sources of supply of hot and cold water to the first-named pipe line, and automatically operable means disposed in the first-named pipe line for admitting water and antiseptic fluid to the perforated pipes disposed on the floor of the shower.

2. In a structure according to claim 1, means for regulating the amounts of water and antiseptic fluid admitted to the perforated pipes.

3. In a shower bath having a shower head and a water pipe leading from a source of water under pressure to the shower head, a source of fluid, a perforated member disposed below the shower head on which a bather may stand, a fluid conducting pipe leading from the source of fluid to the perforated member, a connection between the water pipe and the fluid conducting pipe, and adjustable means in said connection for regulating the amount of fluid which is mixed with the water during its travel to the perforated member.

4. In a shower bath having a shower head and a water pipe leading from a source of water under pressure to the shower head, a source of fluid, a perforated member disposed below the shower head, a fluid conducting pipe leading from the source of fluid to the perforated member, a connection between the water pipe and the fluid conducting pipe, and adjustable means in said connection for regulating the amount of fluid which is mixed with the water during its travel to the perforated member.

5. In a shower bath comprising a shower head

and a water pipe connecting the shower head to a source of water under pressure, control means disposed in said pipe for regulating the flow of water therethrough, a storage tank for antiseptic fluid, spray means disposed near the bottom of the shower bath, a piped connection between the storage tank and the spray means, a second piped connection between the first piped connection and the water pipe, said control means being operable to regulate the flow of antiseptic fluid to the spray means.

6. In a structure according to claim 5, said means for connecting the storage tank to the spray means comprising a valve housing, a branch pipe leading from the water pipe to one end of the valve housing, a branch pipe leading from the storage tank to the other end of the valve housing, means disposed within the valve housing for closing and opening the branch pipe from the storage tank and operable by water pressure from the first-named branch pipe for opening and closing the branch pipe from the storage tank, a third branch pipe extending from the end of the valve housing to which the first-named branch pipe is connected, a fourth branch pipe extending from the end of the valve housing to which the second-named branch pipe is connected, a second valve housing, the third-named branch pipe being connected to one end of the second-named valve housing, and the fourth-named branch pipe being connected to the other end of the second-named valve housing, whereby when water under pressure is admitted to the first-named branch pipe, the means for opening and closing the second-named branch pipe will be actuated, thereby admitting water and antiseptic fluid to the second-named valve housing through the third-named and fourth-named branch pipes.

7. In a structure according to claim 6, means mounted in the second-named valve housing for regulating the relative flow of the water and the antiseptic fluid from the third-named and fourth-named branch pipes, and for entirely stopping the flow of water from the third-named branch pipe.

NOLAN B. WICKER.
